UNITED STATES PATENT OFFICE.

STEPHEN TOTH AND PETER SANKO, SR., OF FURNACE RUN, PENNSYLVANIA.

WEAPON.

1,259,682.

Specification of Letters Patent. Patented Mar. 19, 1918.

Application filed July 26, 1917. Serial No. 182,822.

To all whom it may concern:

Be it known that we, STEPHEN TOTH and PETER SANKO, Sr., subjects of the King of Hungary, and residents of the city of Furnace Run, county of Armstrong, and State of Pennsylvania, have invented certain new and useful Improvements in Weapons, of which the following is a specification.

Our invention relates more particularly to that type of weapon as shown in U. S. Patent #1,188,511, granted to Stephen Toth, on June 27, 1916, consisting essentially of the combination of a sword or bayonet and revolver, the present invention being an improvement in arrangement of the elements thereof, in the attaching and locking provisions for securing the sword or bayonet upon the revolver barrel and in improved means for rendering the revolver secure against accidental discharge while using said sword or bayonet.

The present invention contemplates the easy and rapid attaching and detaching of said bayonet to said revolver, and means for securely locking the bayonet in operative position, and also contemplates the embodiment of means for rendering the revolver operative or inoperative by rendering the trigger thereof operative or inoperative.

With these objects in view, our invention consists essentially of the combination and arrangement of parts shown in the accompanying drawings, it being understood that such modifications thereof may be made as legitimately come within the scope of the appended claims. In the drawings, Figure 1 shows a general side elevation of the improved device; Fig. 2 shows a plan view from the underneath side of the device, a portion thereof being in section taken on line 3'-3' of Fig. 1. Fig. 3 is a sectional elevation showing the mounting and locking means as taken on line 5'-5' of Fig. 1. Fig. 4 is a detail of the locking ring, while Fig. 5 is a section of the revolver barrel, taken on same section as Fig. 3, and showing the opening with which locking ring engages. Fig. 6 shows a detail section of enlarged end of bayonet on same section as Fig. 3.

With more particular reference to the drawings, the numeral 1 indicates the revolver in general, 2 being the barrel and 3 the handle or grip thereof, 4 indicating the rib customarily formed integral with the barrel on its upper side, and carrying the sights 5-5. 6 indicates the trigger, and 7

the trigger guard customarily incorporated with the revolver. To the grip 3 of the revolver 1 any suitable guard or hand shield 8 may be attached. Pivotaly attached at 10 to revolver 1 is a leaf spring 9, carrying a projection or enlargement 11 at its outer extremity, said enlargement being capable of entering or filling the space between the trigger 6 and rear portion of the guard 7, so that when in this position it is impossible to depress the trigger and cause discharge of the weapon. By flexing the spring laterally and oscillating it rearwardly this enlargement is removed from its locking position, allowing the usage of the revolver in its normal manner.

12 indicates a sword or bayonet which is attached at the outer end of barrel 2, and preferably on the lower side of the barrel, so as not to interfere with the use of the sights 5 or with the normal discharge of the weapon, the bayonet 12 being enlarged at its rear extremity, as at 13, said enlargement being bored, as at 14, to snugly engage the periphery of the barrel 2. Enlargement 13 also carries a concentric groove 15 for retaining the locking ring or member 16 to allow only circumferential motion thereof. Ring 16 is provided with a spaced section or opening 18 to allow the longitudinal entrance or retraction of rib 4 therethrough when the ring is moved to the unlocking position, a suitable handle or projection 17 being preferably provided to facilitate the circumferential movement of said ring, a suitable opening 19 being provided through the bayonet or sword blade 12 in alinement with groove 15, and also a suitable opening 20 being provided through rib 4 to co-act with ring 16 for locking said enlargement 13 of blade 12 in fixed position on barrel 2.

In practice when it is desired to use the revolver with the attachment it is necessary merely to move ring 16 so that its opening 18 is alined with rib 4, and to insert the barrel end in opening 14 of enlargement 13 until opening 20 is alined with ring 16, when a slight motion in either direction of ring 16 will securely lock the attachment to the barrel by means of the ends of ring 16 passing through the opening 20 of the barrel rib. To render the revolver secure against discharge spring 9 is flexed until enlargement 11 will pass over guard 7 and enter the space between the back of trig-

ger 6 and the guard 7. It is readily apparent that the device may be used with any standard form of revolver, the only alteration thereof being the provision of an opening 20 through the barrel rib and the attachment of the locking spring 9 as indicated. It is to be understood that enlargement 13 is provided with a longitudinal opening 20' to allow insertion of rib 4 therethrough and by virtue of the rib engaging with the sides of this opening the blade is prevented from rotation or circumferential displacement on the barrel 2 of said revolver.

15 What we claim as new, and desire to protect by these Letters Patent, is:

In combination with a revolver or pistol, a sword or cutting blade, having one end thereof enlarged to surround a portion of 20 said barrel, said enlargement having a circumferential groove carrying a rotatable or circumferentially movable ring, said ring

having a handle or projection to facilitate its movement, a portion of said ring being cut away to allow the passage of revolver rib 25 therethrough, and opening through said revolver rib for engagement with said ring, a spring carrying an enlarged projection being attached to said revolver to co-act with the revolver trigger and trigger guard 30 to prevent accidental discharge of said revolver, substantially as described.

In testimony whereof we have signed our names to this specification in the presence of two subscribing witnesses.

STEPHEN TOTH.
PETER SANKO, Sr.

Witnesses as to Stephen Toth:

T. A. SPERRY,
HELEN HUNT.

Witnesses as to Peter Sanko, Sr.:

G. A. WALKER,
CLARENCE O. MORRIS.
